TIMER INDICATOR AND CONTROL DEVICE FOR GRENADE

Irwin R. Barr, 110 Martingale Road, Lutherville, Md., and
Robert W. Schnepfe, Jr., 111 Cinder Road, Timonium,
Md.

Filed Sept. 8, 1965, Ser. No. 86,911

Term of patent 14 years

(Cl. D30—1)

FIGURE 1 is an isometric view of a timer indicator and control device for grenade embodying the design according to the invention.

FIGURE 2 is a top plan view of the embodiment of FIGURE 1.

FIGURE 3 is a bottom plan view of the embodiment of FIGURE 1.

FIGURES 4-7 are elevational views as taken from positions turned 90° from one another about the annular periphery of the embodiment.

We claim:

The ornamental design for a timer indicator and control device for grenade, as shown.
